[57] ABSTRACT

A high power klystron including means for forming an electron beam, preferably a hollow electron beam, with a perveance which is greater than 3 and means for defining interaction paths including delay line type structures in resonator chambers as sections with extended interaction.

HIGH POWER KLYSTRON

BACKGROUND OF THE INVENTION

1. Field of the Invention

This invention relates to high power klystron particularly for television transmission, with an electron beam producing system, in which a number of resonator chambers are permeated by an electron beam which is extended therethrough in a reduced beam bundle, and an electron beam collector device.

2. Description of the Prior Art

High power klystrons are preferably utilized in the ultra high frequency (UHF) range for the transmission of television programs, whereby high transmission qualities are of primary importance in the UHF range. In order to comply with the high demands placed on the transmission and in particular to the requirement for linearity in amplification, klystrons for television applications must be operated with a beam permeance of the electron beam which is smaller than 2 (reference here being taken to "Rundfunktechnische Mitteilungen," volume 12, 1968, issue 6, pages 262-268, as well as "NTZ," 1966, issue 6, beginning at page 365). The reason for this is that the high, merely positive, electron stress on the resonators due to the electron beam. It is furthermore stated that, in order to obtain the television qualities required, the qualities of the resonators should essentially be determined by the externally applied stress.

SUMMARY OF THE INVENTION

In contrast to these prior art klystrons for television applications, it is proposed according to the present invention that a high power klystron of the above-mentioned kind have a permeance which is greater than 3 for the electron beam, which beam is preferably formed as a hollow beam, and that the interaction paths are designed as sections with extensive interaction by providing delay line like structures, which structures are known per se, in the resonator chambers of the klystron.

Klystrons with extended interaction, generally called "Extended Interaction Klystrons" are known in the art, they have heretofore been driven with electron beams having a permeance that is less than 2. Here, compare "IRE TRANSACTIONS ON ELECTRON DEVICES", January 1961, pages 44-55, in particular at page 49, left-hand column near the bottom.

The present invention therefore proceeds from the recognition that the electron stress depends strongly on the beam speed in a resonator cavity with distributed or strongly extended interaction. With a suitable selection of the beam speed, the electronic stress can be made almost zero. This is also valid for permeance values which are greater than 2 (i.e. $2 \cdot 10^{-6} \text{ A/V}^{3/2}$). It has been shown that the permeance of the electron beam is only limited by the fact that the average center geometric distance of two successive resonators must be a fourth of the plasma wave length, and thereby the resonator chambers are still sufficiently decoupled with respect to high frequency.

BRIEF DESCRIPTION OF THE DRAWING

Other objects, features and advantages of the invention will be best understood from the following detailed

description taken in conjunction with the accompanying drawing which carries a single FIGURE showing an elevational cross-sectional view of a high power klystron constructed in accordance with the principles of the present invention.

DESCRIPTION OF THE PREFERRED EMBODIMENT

Referring to the drawing, a highly permeant hollow electron beam 18 is produced by an electron beam producing system 1 which comprises a wing-shaped cathode 2, which has an end thereof surrounded by Wehnelt electrode 3. A pulling anode 4 is preferably defined as a modulation anode and is disposed adjacent to the electrode 3 and generally aligned therewith axially of the klystron. The electron beam 18 traverses the klystron generally about the longitudinal axis thereof to reach an electron beam collector 8 which is provided with cooling plates 7, after first having permeated a series of resonator chambers 5 and 6. Suitably arranged and dimensioned electromagnets 9 are provided to effect guidance of the electron beam through the tube without permitting radial dispersion of the beam, the entire magnet arrangement being preferably arranged between a pair of pole plates 10.

The sample embodiment set forth in the figure illustrates a klystron having a plurality of chambers, say a five-chamber klystron, and for the sake of simplicity, the second and third chambers have not been illustrated, which chambers are however constructed to correspond to the resonator chambers 5. The fifth resonator chamber 6 differs somewhat from the construction of the preceding resonator chambers 5 in order to provide an optimum adaptation of the reduced electron beam speed. Spiral-shaped delay structures 11 and 12 are provided in the resonator chambers in order to form a broad-band extended interaction zone corresponding to the aforementioned and so-called "extended interaction," in place of the usually narrow-band interaction between the beam and interaction gaps.

In order to prevent interfering backward-facing waves on the delay sections 11 and 12, measures have been provided which are in themselves known in the art and which are not illustrated here for the sake of simplicity and clarity. The delay structures 11 and 12 are connected with internal conductors 13, 14 and 15 of coaxial decoupling members which are respectively sealed with respect to the vacuum within the resonator chambers by means of ceramic windows, the windows 16 and 17 being illustrated in the drawing.

Although we have described our invention by reference to a specific illustrative embodiment, many changes and modifications may be effected by those skilled in the art without departing from the spirit and scope of our invention, and it is to be understood that we intend to include within the patent warranted hereon all such changes and modifications as may reasonably and properly be included within the scope of our contribution to the art.

WHAT WE CLAIM IS:

1. In a high power extended interaction klystron of the type which includes an electron beam producing system, a number of resonator chambers which are permeated with an electron beam which is extended in a

reduced bundle, and an electron beam collector for receiving the electron beam, the improvement therein comprising means for producing the electron beam as a hollow beam with a perveance which is greater than 3, and means defining interaction paths including delay line structures in the resonator chambers which are operable as sections with extended interaction.
